CLAIM

The ornamental design for a bleed ring as shown and described.

DESCRIPTION

FIG. 1 is a perspective side view of the bleed ring according to an embodiment of the presently disclosed subject matter.

FIG. 2 is a top side view of the bleed ring of FIG. 1.

FIG. 3 is a front side view of the bleed ring of FIG. 1.

FIG. 4 is a left side view of the bleed ring of FIG. 1.

FIG. 5 is a back side view of the bleed ring of FIG. 1.

FIG. 6 is a right side view of the bleed ring of FIG. 1.

FIG. 7 is a bottom side view of the bleed ring of FIG. 1.

FIG. 8 is a perspective side view of the bleed ring according to an alternate embodiment of the presently disclosed subject matter.

FIG. 9 is a top side view of the bleed ring of FIG. 8.

FIG. 10 is a front side view of the bleed ring of FIG. 8.

FIG. 11 is a left side view of the bleed ring of FIG. 8.

FIG. 12 is a back side view of the bleed ring of FIG. 8.

FIG. 13 is a right side view of the bleed ring of FIG. 8; and, FIG. 14 is a bottom side view of the bleed ring of FIG. 8. The broken lines shown in the figures are for the purpose of illustrating portions of the bleed ring and form no part of the claimed design.
